Application May 26, 1951, Serial No. 15,320

Term of patent 3½ years

(Cl. D3—19)

To all whom it may concern:

Be it known that I, James J. Mulcrone, Sr., a citizen of the United States of America, residing at Minneapolis, in the county of Hennepin and the State of Minnesota, have invented a new, original, and ornamental Design for a Combined Scissors Sheath and Spool Holder, of which the following is a specification, reference being had to the accompanying drawing, forming a part thereof.

The figure on the drawing is a front perspective view of a combined scissors sheath and spool holder, showing my new design.

The side and back of the design, not shown, are conventionally plain.

I claim:

The ornamental design for a combined scissors sheath and spool holder, as shown and described.

JAMES J. MULCRONE, SR.
